G. F. CANE

FOLDABLE BED SUPPORTING MEANS

Filed Jan. 18, 1922

INVENTOR
GORDON F. CANE

BY

Joseph B. Gardner
his ATTORNEY

UNITED STATES PATENT OFFICE.

GORDON F. CANE, OF OAKLAND, CALIFORNIA, ASSIGNOR TO AMERICAN AUTOMATIC LOCK AND LIFT COMPANY, OF SAN FRANCISCO, CALIFORNIA, A CORPORATION OF CALIFORNIA.

FOLDABLE-BED-SUPPORTING MEANS.

Application filed January 18, 1922. Serial No. 530,169.

To all whom it may concern:

Be it known that I, GORDON F. CANE, a citizen of the United States, and a resident of Oakland, county of Alameda, State of California, have invented a certain new and useful Foldable-Bed-Supporting Means, of which the following is a specification.

My invention relates to the supports which carry the swinging bed-frame of particularly the type of foldable bed which in the folded position is adapted to move in a horizontal plane.

An object of the invention is to provide supporting means of the character described which insures maximum strength combined with beauty of design and simplicity of construction.

Another object of the invention is to provide means of the character described which enables the bed to be readily installed.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a perspective view of the head end of a foldable bed provided with the supporting means of my invention.

Figure 2 is a fragmentary section of the lower portion of the head end of the bed.

Briefly expressed the invention in its present embodiment comprises a pair of supports adapted to lie at the sides of the bed and arranged to be attached to the lower edge of a panel or the like such as is mounted to swing about a vertical axis. The supports at a point spaced from the panel carry a bed frame for pivotal movement about a horizontal axis. Adjacent the panel the supports are provided with upwardly protruding integral studs which are arranged to extend well up into and lie concealed within the hollow side posts of the head-board of the bed, the head-board being fixed to the panel near its upper end. In this manner the supports, while being secured to the panel unobtrusively, are

nevertheless held rigidly and rendered fully capable of carrying the bed frame in the folded position.

A detailed description follows:

The foldable bed 2 shown in the drawings is of the type adapted in the folded position to swing about a vertical axis to and from a position of concealment. In the present embodiment the bed is arranged to be secured to a panel 3 mounted to allow of the swinging movement just noted. The bed is primarily supported on a pair of brackets or supports 4 and 5 which are arranged to lie at opposite sides of the bed and are provided with transversely extending ears 7 adapted to lie adjacent the bottom of the panel and through which extend the screws 8 that secure the supports to the panel. The supports extend perpendicularly from the panel and are connected by pivots 9 to a bed-frame 12 whereby the latter may swing about a horizontal axis to and from a folded position. Preferably formed integral with the supports and positioned adjacent the ears 7 are upwardly extending studs 13 over which the hollow posts 14 of the head-frame 15 are adapted to fit. The studs are comparatively long and are arranged to be completely concealed within the posts. The upper and lower ends 17 and 18 of the studs are about of the same width as the inside of the posts, so that a snug fit is permitted when the studs are engaged in the posts. The head-frame 15 which as here shown is in the shape of an inverted U is fixed to the panel independent of the supports 4 and 5 by means of bolts 19. The latter are located near the top of the head-board so that a comparatively large portion of the head-board is made use of as a lever for resisting the tension of the supports due to the weight of the structure supported thereby.

It will be clear that since the studs are concealed, practically the only visible portion of the supports is the body thereof; and since the body somewhat resembles the side posts an extremely harmonious appearance is presented.

I claim:

1. In a bed movable as a whole in a horizontal plane, a pair of brackets adapted to be fixed to a movable panel or the like and arranged to lie at the sides of the bed, a bed-frame pivotally supported on said

- brackets for movement in a vertical plane, upwardly extending studs formed on said brackets, a head-frame comprising a tubular member having vertical side posts open at their lower extremities whereby said studs may be inserted within said posts, and means adjacent the upper extremities of said posts for attaching said head-board to said panel.
- 5 2. In a bed of the character described, a supporting member, brackets secured thereto, a bed frame pivotally mounted on said
- brackets for movement in a vertical plane, upwardly extending studs on said brackets, a head frame including vertical hollow 15 posts open at their lower extremities for the reception of said studs, and means for attaching said headboard to said supporting member adjacent the top of said head-board.
- 20 In testimony whereof, I have hereunto set my hand at Oakland, California.

GORDON F. CANE.
